HAMMERING MACHINE

Walter Gleissner, Weissenfels-on-the-Saale, Germany, assignor to the firm Nollesche Werke Kom. Ges., Weissenfels-on-the-Saale, Germany

Application March 31, 1934, Serial No. 718,366
In Germany April 4, 1933

5 Claims. (Cl. 12—51)

The invention has for an object an improvement in automatically rotatable shoe supports.

The improvement relates according to the invention both to the control movement of the hammering tools and also to the movement of the shoe, whose seam insertion, on the shoe bottom to be hammered must be carried past the tools always at a definite angle. The hammering tools which consist for example of a hammering drum and a side hammer located thereunder must be so guided to the shoe that in every case the side hammer bears against the shoe before the hammering drum comes into contact with the edge of the shoe in order to avoid injury to the shoe edge that is to be hammered. This is brought about by the feature that the carrier of the hammering tools during its movement to and from the shoe controlled by a cam device is given by a second cam device a supplementary movement such that the tool treating the edge of the shoe comes into action on the shoe before the tool treating the bottom of the shoe, the support of which is given a longitudinal movement and a swinging movement by a cam disk. The shoe support is swung during transference from the treatment of the heel surface to the treatment of the toe surface so that the two surfaces, which are inclined to each other, assume successively the same horizontal position in relation to the tools. The last-support is arranged so as to be longitudinally movable on a sliding-carriage guide and the sliding-carriage guide itself is capable of being swung about a horizontal pin. The longitudinal movement and the angle of inclination of the shoe bottom can be adjusted without interference inter se. The last-support which during its rotation is moved in the longitudinal direction of the last and swung out, can be adjusted by adjusting devices so as to execute swings and also longitudinal movements of different magnitudes. The adjusting devices are inserted in the gear by means of which the swinging and the longitudinal movements are produced.

The subject-matter of the invention is represented in illustrative constructional forms in the drawings, in which—

Figure 1 is a general view of the machine,

Figure 2 is a section through the carrier of the hammering tools,

Figure 3 a side view of the controlling device, and of the carriers for the hammering tools and of the rotatable block for the shoe-moving device,

Figure 4 is a transverse view of the controlling gear for the hammering tools,

Figure 5 is a side view of the controlling device and of the hammering tools at the instant of the application of the side hammer to the edge of the shoe,

Figure 6 is a side view of the controlling device and of the hammering tools in the case of the positive application of the side hammer and the hammering drum,

Figure 7 is a plan of a shoe bottom,

Figure 8 is a front view of the rotary body carrying the shoe,

Figure 9 is a side view of the rotary body,

Figure 10 is a plan of the cam disk with a controlling slide,

Figure 11 is a section corresponding to the line 11—11 of Figure 8,

Figure 12 is a section through the rotary body with the adjusting elements,

Figures 13 and 14 are rear views of the rotary body with the shoe carrying device during the treatment of the toe portion of the shoe,

Figures 15 and 16 show positions during the treatment of the heels and of the shoe toes,

Figures 17 and 18 show different positions of the sliding carriage guide,

Figures 19 and 20 are plans of the star wheels in different positions.

Driving device for the hammering tools and the block carrying the shoe-last

In the machine casing 1 there is mounted the driving shaft 3, which is in engagement with the worm-wheel 5 fastened on the shaft 91. On this shaft 91 there are freely rotatable the bevel wheels 8 and 9, which serve for the alternate driving of the controlling shaft 13 and of the driving wheels 47, 48, 50, 51. The shaft 3 and the worm-wheel 5, the intermediate shaft 91, and the coupling sleeve 7 movably mounted on this shaft revolve continually. The machine is started by the pedal 70, which can be put into the three positions I, II, III. Position I is the position of rest.

The controlling slide 73 can be moved downwards by the pedal 70 by means of the rod 71 which is under the action of the spring 85, and of the toothed-segment lever 72. The slide 73 controls the controlling part 77, which according to its position couples the coupling sleeve 7 either with the bevel wheel 8 or with the bevel wheel 9. The return of the controlling part 77 and consequently of the coupling sleeve 7 into the position of rest is effected by means of the cam disk 86, 86', which is fastened on the shaft 13 and co-operates with

the guiding roller 83 of the controlling slide 73. From the coupling sleeve 7 there are driven either through the bevel wheel 8 or through the bevel wheel 9 the wheels 10, 46, 11, 12, and consequently 5 the shaft 13. From the toothed-wheel 46 there are driven the toothed wheels 47, 48 and the cam disk 49 rigidly connected with this toothed wheel 48. The shaft of the toothed wheel 47 drives the star wheel 50, which is connected with the 10 star wheel 51 (Figures 19 and 20). The star wheels 50, 51 effect the partial rotation of the rotary body 52, whilst from the toothed wheels 47, 48 the cam disk 49 is constantly and uniformly rotated.

15 From the driving shaft 3 by means of a belt
driving device there is moved the eccentric shaft
22, from which is effected the driving of the ham-
mering tools. The rotation of the shaft 22 is
transmitted through the toothed wheels or in-
20 termediate wheels 109, 110, 111 to the toothed
wheel 114 located on the shaft 112 of the hammer-
ing drum 113. The hammering drum 113 is thus
rotated in the direction of the arrow (Figure 2).
Under the hammering drum the side hammer
25 115 is carried in the tool carrier 100. It is moved
to and fro by means of an eccentric portion of the
shaft 22. For this purpose the eccentric portion
of the shaft 22 is grasped by a connecting rod
116, which engages by means of a pin 117 in a
30 guiding block 118, which transmits the to and fro
movement to the side hammer 115.

Against the arm 99 of the tool carrier 100 there bears a spring 107, the other end of which bears in the projection 106 against the adjusting spindle 105. The spring 107 serves as an adjustable counterpoise to the weight of the tool carrier and the hammering tools.

Control and mode of operation of the hammering tools

In the machine casing 1 there is mounted on a shaft 2 an oscillatory lever 16, which has two lower arms 16' and 16'' and which is controlled from the cam disk 14 fastened on the shaft 13 by means of a cam roller 15 arranged on the arm 16'. On the other lower arm 16'' there is mounted so as to be oscillatable about a bolt 120 the controlling lever 101, against the projection 101' of which bears by means of the abutment screw 44 the tool carrier 100 mounted on the shaft 22. In the slot 101'' of the lever 101 engages a pin or sliding block 122 mounted on the controlling lever 123. The controlling lever 123, which is rotatable on the shaft 2, is moved by the cam disk 125 by means of a cam roller 124 and consequently controls the controlling lever 101. In consequence of the co-operation of the two cams 14 and 125 which are both fixed on the shaft 13, the point Sch of the hammering drum 113 and of the side hammer 115 describes the path SB (Figure 3). During the guidance of the tools to the shoe the oscillating lever 16 is turned with its two arms 16' and 16'' about the shaft 2, so that the position of the bearing bolt 120 is changed. As soon as the side hammer 115 bears against the shoe (Figures 5 and 6), the cam 14 comes out of operation because the arm 16' can with the roller 15 no longer swing back against the cam. The bearing bolt 120 then stands still. By the further rise of the cam 125 the cam roller 124 is swung out upwards and consequently the lever 101 is brought out of the position shown in Figure 5 into the position shown in Figure 6, in which there is a space between the projection 101' of the controlling lever 101 and the adjust-

ing screw 44 located in the tool carrier 100. In consequence of the swinging of the controlling lever out of the position shown in Figure 5 into the position shown in Figure 6, the tool carrier 100 can swing about its axle 22 and the hammering drum can bear against the bottom of the shoe. By this construction it is brought about that the hammering drum 113 descends upon the bottom of the shoe only after the side hammer has come to bear upon the edge of the shoe. In 10 regard to this it is quite immaterial whether it is a question of treating left or right shoes with a narrow or a broad ball portion. In this case it cannot occur that the hammering drum in the case of a particularly one-sided ball portion of a 15 shoe descends upon the bottom before the side hammer has reached the edge of the shoe. This is due to the fact that the bearing bolt 128 of the controlling lever 101 is located in the swinging-out arm 16'' of the oscillatory lever 16 and 20 the lever 101 on the oscillation of the lever 16 about the axle 2 allows the descent of the hammering drum 113 only after the side hammer 115 has come into contact with the edge of the shoe. In the position shown in Figure 6, the hammering tools are no longer under the influence of the cam disks 14 and 125 so that they conform to 25 the varying contours of the shoe during its movement.

During the guidance of the tools to the shoe 30
 68, the shoe is moved by the cam disk 49 from
 the connecting portion G' or G'' (Figure 7) to-
 wards the ball portion Ba' or Ba''. As, now, the
 distance b'' of the inner side Ba'' of the ball portion
 from the longitudinal centre line F—S is 35
 less than the distance b' of the outer side Ba' of
 the ball portion, the tools have in this case during
 their guidance to pass through a greater distance
 than on the side Ba' of the ball portion. The
 shoe executes during this difference of travel a 40
 longitudinal movement L''—L'; the tools conse-
 quently come later into operation.

The cam 125 is formed in relation to the cam 14 in such a manner that the desired action is always secured at the beginning and at the end of the removal of the tools at the shank of the shoe.

Operating and adjusting devices for the movement of the shoe

In the rotary body 52 the slide-guiding body 127 is mounted so as to be oscillatable about a bolt 126. To this body 127 the intermediate member 128 is connected by means of the pivot bolt 129. The other end of the member 128 is connected to the controlling lever 130 by means of a bolt 131 that is adjustably in the slot 130'. The head 131' of this bolt projects laterally out of the rotary body 52 (Figure 11). The controlling lever 130, which is mounted so as to be rotatable about the bolt 132, is connected with the controlling slide 135 by means of the rod 133 and the bolt 134 (Figure 8). From the cam disk 49 a to and fro movement is given to the controlling slide 135 mounted in the rotary body 52 by means of the roller 136 and the bolt 137. To the controlling slide 135 there is connected by a bolt 139 a lever which is guided by a guiding piece 140 bearing on the sliding edges 138'. This guiding piece comprises a bolt 140', which is mounted in the sliding body 141. The sliding body 141 is movable in the slots 52' of the rotary body 52 and is grasped in its middle portion by the prongs of a forked lever 144, which is fastened on the bolt 143 on which likewise is fast the adjusting 75

lever 142. By higher or lower placing of the adjusting lever 142 on its fixing bar 142' the lever 138 is swung about its pivot bolt 139 by means of the forked lever 144, the sliding piece 141, and the guide piece 140, and in this way the sliding carriage 148 can be adjusted on the slide guiding body 127 because the lever 138 is connected with the slide 143 by means of the intermediate member 146 and joints 145 and 147. From the lever 142, there is effected consequently the adjustment of the sliding carriage 148 on the slide body 127 in accordance with the length of the shoe, as shown in Figures 13 and 14. In the position of the sliding carriage and of the controlling slide 135 shown in Figure 8 there is no movement of the sliding carriage because in this case the slot 52' extends in the same direction as the sliding surfaces 138' of the lever 138.

The rotation of the rotary body 52 is brought about by the star wheels 50, 51, by which the shoe support is given a half revolution when the heel or toe portion of the shoe is swung out against the tools by the wave of the cam disk 49. By the controlling slide 135 there are simultaneously produced by means of the rod 138 the longitudinal movement of the sliding carriage 148 and by means of the rod 133 turning about the bolt 134 and of the controlling lever 130 a swinging of the sliding carriage guide 127 about the bolt 126. The magnitude of the angle of the swing is adjusted by means of the head 131' independently of the longitudinal movement of the sliding carriage so that the angular position of the sliding carriage guide 127 may be the same in the case of different longitudinal controlling effects on the sliding carriage 148 (Figures 13 and 14). As the inclination of the toe to the heel is of different magnitudes in the case of different forms of shoes, it is necessary to have a different angle of swing of the sliding carriage guide, which may be produced by moving the bolt 131 in the slot 130' of the lever 130. By this movement the position of the sliding carriage guide is altered only during the treatment of the toe (Figure 16) but not during the treatment of the heel (Figure 15).

In the case of the constructional example above described the swinging of the sliding carriage guide 127 and consequently of the shoe 68, is distributed over the entire duration of the longitudinal control of the sliding carriage 148. If now it is desired to swing the shoe only temporarily during the longitudinal controlled movement of the shoe, for example only during the treatment of the toe portion, this can be brought about by arranging a special cam groove for the movement of the lever 130 after the manner of the example shown in Figure 12. Whilst previously the longitudinal controlled movement and the swing of the shoe were effected by means of the cam groove 49' of the cam 49, in this case the swing of the shoe is effected by means of the special cam groove 49''. A controlling rod 153 movably mounted in the rotary body 52 is moved by means of a cam groove 49'' by means of a roller 151 on the bolt 152. In the slot 130' of the controlling lever 130 there engages a bolt 154 of the sliding rod 153. The controlling lever 130 is mounted in the supporting block 59 so as to be rotatable about bolt 132 as in the case of Figure 8. The adjustment of the angle of swing is effected exactly as hereinbefore described.

The heel support 149 is fixed, whilst the toe support 150 is arranged to be movable on the sliding carriage 148 in accordance with the size of the shoe.

What I claim is:—

1. In a hammering machine with a shoe support capable of being rotated mechanically, a tool carrier, a series of hammers supported on said carrier, a cam device controlling the tool carrier during its movement to and from the shoe, a second cam device giving a supplement movement to the tool carrier such that the tool treating the edge of the shoe, comes into action on the shoe before the tool treating the bottom of the shoe, a further cam device, by which a longitudinal movement and a swinging movement is given to the support of the shoe.

5

2. In a hammering machine with a shoe support capable of being rotated mechanically, a tool carrier, a cam device controlling the tool carrier during its movement to and from the shoe, a second cam device giving a supplement movement to the tool carrier such that the tool treating the edge of the shoe comes into action on the shoe before the tool treating the bottom of the shoe, a lever controlling the supplementary movement of the tool carrier and connected to a prolongation of the lever for swinging the tool carrier by means of an axle located outside the pivotal axle of the swinging lever, a lever mounted on the pivotal axle and controlled by the second cam device and coupled to the lever controlling the supplement movement.

10

3. In a hammering machine with a shoe support capable of being rotated mechanically, a tool carrier, a cam device controlling the tool carrier during its movement to and from the shoe, a second cam device giving a supplement movement to the tool carrier such that the tool treating the edge of the shoe comes into action on the shoe before the tool treating the bottom of the shoe, a further cam device, by which a longitudinal movement and a swinging movement is given to the support of the shoe, an adjustable linkage, effecting the longitudinal and swinging movement of the shoe support.

20

4. In a hammering machine with a shoe support capable of being rotated mechanically, a tool carrier, a cam device controlling the tool carrier during its movement to and from the shoe, a second cam device giving a supplement movement to the tool carrier such that the tool treating the edge of the shoe comes into action on the shoe before the tool treating the bottom of the shoe, a further cam device, by which a longitudinal movement and a swinging movement is given to the support of the shoe, a slide controlled from the further cam device and transmitting its movement to the last-support and the sliding carriage.

25

5. In a hammering machine with a shoe support capable of being rotated mechanically, a tool carrier, a cam device controlling the tool carrier during its movement to and from the shoe, a second cam device giving a supplement movement to the tool carrier such that the tool treating the edge of the shoe comes into action on the shoe before the tool treating the bottom of the shoe, a further cam device, by which a longitudinal movement and a swinging movement is given to the support of the shoe, a slide controlled from the further cam device and transmitting its movement to the last-support and the sliding carriage by oscillatory levers the effective lengths of which are adjustable independently of one another in such a manner that longitudinal movements and swinging movements differing in magnitude can be produced.
